SELECTOR MECHANISM FLOOR UNIT

Serge Mignocchi and Louis Mignocchi, New York,
N. Y., assignors to Serge Elevator Co., Inc.,
Bronx, N. Y.

Application October 15, 1945, Serial No. 622,464

17 Claims. (Cl. 175—335)

1

The present invention relates to a floor selector utilized in automatic elevator systems, such as the push-button type.

In elevator systems of this type, in order to automatically bring the car to a selected floor in response to a call impressed with a push-button in the hall or in the car, certain mechanism is used for automatically closing and opening the electrical circuits which control the operation of the motors used in the system. This mechanism includes direction switches, which determine the direction of motion of the elevator car in response to a call, a relay that corresponds to each floor and switches that are opened and closed by the car movement to control the floor relay and the car stopping relay. These elements and the mechanical means that operate them and which is directly connected to the car movement are together known as the floor selector.

Heretofore these elements were mounted on a panel board in groups corresponding to each other and not to the particular floor for which they operated the car and were usually therefor so separated from each other that floor selectors of the prior art occupied relatively considerable space. Further, with prior art floor selectors, since all the elements of the selector corresponding to a particular floor were not grouped together in the same space as a unit, they did not lend themselves to ready and easy inspection for repair or replacement should the selector for that particular floor, for some reason be out of order.

The present invention therefore contemplates an integral unit for each floor that has mounted on it all the switches and contacts that correspond to each floor and which integral unit is so arranged that the elements thereof will be operated in proper sequence by the car movement.

The present invention contemplates the provision of a floor unit that has mounted on it a floor relay and the contacts therefor, the up and down direction switches, the switch contacts which control operation of the floor relay and the stopping relay and a cam that is so constructed and arranged that the switches are opened and closed in proper sequence so that the car will properly respond to the signal impressed on the hall or the car button and place the system in condition to stop the car when it reaches the floor to which it has been called.

There is thus provided a floor selector unit in which all of the elements of the automatic system corresponding to each floor are grouped together in a comparatively small space so that the

2

selector mechanism is small and compact and lends itself to ready and easy inspection.

As is well known, the distance between each floor may vary or the position of the follower that operates the floor selector may change somewhat during operation so that it will not accurately correspond to the position reached by the elevator at the floor corresponding to the selector unit so that the car may be stopped above or below the floor level, a circumstance that it is desired to avoid.

The present invention therefore also contemplates the provision in a directly connected floor of a readily adjustable means for each selector unit whereby the position thereof relative to the position of the car in the hatchway may be adjusted in the event that they become misadjusted, so that the car will be stopped when it is positioned at the floor corresponding to the selector unit.

The present invention still further contemplates the provision of a non-rigid resilient connection between the selector unit and the follower that is driven by the movement of the car so that no strain is placed on the connection as the follower travels past the connection thereby eliminating probability of resulting damage to the connecting means.

The present invention still further contemplates the provision of a floor unit for a selector mechanism that is standard in all its parts and may be utilized without change to various types of buildings and various types of automatic elevator systems.

These, other and further objects, advantages and uses of the present invention will be clear from the description which follows and the drawings related thereto in which:

Fig. 1 is a front elevation of a selector mechanism, according to the present invention, the front cover being broken away to show the arrangement of the floor unit comprising it and the traveller positioned at a terminal;

Fig. 2 is a partial front elevation thereof, the follower position at the other terminal;

Fig. 18 is a schematic outline of one cam nose;

Fig. 19 is a schematic outline of the other cam nose;

Fig. 20 is a partial schematic wiring diagram, just sufficient for an understanding of the invention.

Referring now to the drawings and particularly to Figs. 1, 2, 3 and 5, a floor unit 10, one for each floor served by the elevator system, in the illustration six floors and a basement, is arranged in the housing 12 and secured thereby by any satisfactory means, provision being made therefore as by the openings 14 in the member 16, which will receive the required supporting crews (Fig. 6).

The traveler or cross-head 18, which drives the operating cam 20, of each unit and which cams are mounted for oscillation on the shaft 22 in each selector unit 10, is driven by the worm shaft 24.

The cam 20 and shaft 22 are tensioned in operative position by means of the spring 23 expanding between the washers 25 and 27.

The shaft 24 is journaled in suitable bearings mounted in the side walls 26 and 28 and is operatively driven through the gear 30 which is connected directly to the elevator car in any suitable manner so that the shaft 24 will move in accordance with the movement of the elevator car.

The traveler 18 is provided with internal threads (not shown), which mesh with the worm threads 32 on the shaft 24 so that rotation of the latter will cause operative reciprocation of the traveler between the selector unit 34, corresponding to one terminal floor, such as the basement of the building, and the selector unit 36, corresponding to the other terminal floor, such as the top or sixth floor of the building (Figs. 1 and 2).

Movement of the traveler 18 from the one terminal position illustrated in Fig. 1 at the unit 34 to its other terminal position at the unit 36 (Fig. 2) and corresponding to the movement of the elevator car brings the follower 38 extending therefrom into engagement with the resilient arm 42 mounted on a cam 20 positioned in its path of movement.

When the car is positioned at a floor corresponding to a unit 10, the follower 38 rests between the arms 40 and 42 of that floor unit. This is illustrated in Fig. 1, when the car is at the basement floor and Fig. 2 when the car is at the sixth or top floor of the building.

In these positions, the arms 40 and 42 are in a substantially straight vertical position, whereat as will be described, the up and down direction switches are opened by the selector unit and the

stopping coil switch has been closed to stop the car.

As the follower 38 engages the arm 42 and continues its movement, each cam 20, the arm 42 of which is engaged, will be rotated from the position illustrated in Figs. 1, 5 and 11, whereat they point to the traveler that is positioned below them, into the position illustrated in Figs. 2 and 14, whereat in the latter position the follower 38 has cleared the arm 40 and moved past it, the arms 40 and 42 now pointing to the traveler positioned above them.

As we shall in more detail describe, when the traveler is below a unit the up directional switches for the floors above it will have been closed and the down directional switches opened by the cam movement operated by the movement of the follower 38 against the arm 42 and when the traveler is above a unit, the down directional switches for the floors above it will have been closed and the up directional switches opened by the cam movement operated by the movement of the follower 38 against the arm 40.

As will be also explained in further detail this movement of the cam 20 about the shaft 22 also operates the switch contacts (to which we will later refer) of the floor selector which control the starting and the stopping of the car in response to the registration of a call.

Movement of the traveler, under the influence of the car as it drives the shaft 24, from its upper limit position at the unit 36, brings the follower 38 into engagement with the other resilient arm 40 to move the cam, the arm of which is engaged about its shaft 22 in the opposite direction to again cause the switch contacts to close and open for the purposes that we shall further describe.

It will thus be seen that movement of the traveler 18, by the elevator car, oscillates each cam 20 as it moves therewith in either direction, movement from right to left of Fig. 1 corresponding to movement of the elevator car from the basement of the building to the top floor thereof and movement from left to right of Fig. 1 corresponding to movement of the elevator car from the top of the building, to the basement.

In order to insure that the traveler 18 operates in a truly horizontal position so that it will be relieved of strain and insure unvarying engagement of the arms 40 and 42 by the follower 38, we mount the traveler 18 on the angle support 44, so that the traveler 18 reciprocably slides thereacross between the right and left of Fig. 1.

The follower 18 is provided with the upstanding elements 17 and 21, in the space between which the member 19 is seated, the elements 17 and 19 being integral and connected at the underside of the follower.

The member 19 is pivoted to the follower 18 by means of the pin 23 so that it may be raised in rotation in a counter clockwise direction as viewed in Fig. 2 and lowered, when rotated in a clockwise direction as viewed in Fig. 2, by the spring 48.

The angle 46 is secured to the underside of the follower 18, which connects the elements 17 and 21. The horizontal leg of the angle 46 is spaced from the underside of the follower 18. In the space formed thereby, the horizontal leg of the stationary angle 44 is seated.

This construction thereby prevents any rotation or displacement of the follower in a counter clockwise or clockwise direction about the shaft 24, as viewed in Fig. 2, under the influence of the

movement of the traveler 18 by the worm gear 32.

The angle support 44 may be secured in any suitable manner in the housing 10 and the angle 46 secured in any suitable manner to the follower 18. Thus, it will be recognized that the angle 46 reciprocates as a unit with the follower on the stationary angle support 44.

The traveler 18, which moves on the angle 44 thereacross, is resiliently held thereon by means of the tension spring 48, one end of which is secured to the head 50 mounted on the internally threaded collar 52 extending from the traveler and which meshes with the thereads 32. The other end of the spring 48 is secured to the pin 54 which is secured to the member 19 and which pin extends down through the elongated opening 25 in the integral connection between the elements 17 and 21.

Thus the spring 48, which is contractable, normally pulls the members 19 about the pivot 23 against the bottom connecting means between the elements 17 and 19 and urges the follower 18 thereagainst as it is moved across the angle support 44.

In operation, one of the selector units 34 may be manually displaced so that it should be in either the "down elevator" or "up elevator" position when it is in fact in the opposite position. The construction just described, serves to prevent damage to the traveler and the arms 40 and 42 in the event of such displacement. The traveler 18 is thereby permitted to pass over a thus misplaced selector unit 34 because the member 19 may be raised up against the tension of the spring 48 when the follower 38 engages an arm of the misplaced selector unit.

On return of the traveler 18 in the opposite direction of its movement, the misplaced selector unit is now in the proper up or down elevator position corresponding to that of all the other selector units.

Referring now particularly to Figs. 6 and 9, each unit 10, is preferably built from a bracket 56 on one face 58 of which the floor relay 60 is mounted as by any satisfactory means. Separating the face 58 from the relay coil 60, we provide the insulating member 62 on one side of which is secured one lead 64 (Fig. 11) and on the other side of which is secured one lead 66 (Fig. 6), to which leads reference will be further made when the schematic wiring diagram is described. At this point, it is necessary to point out only that the lead 64 is free at one end so that it will be connected to one side L2 of the line.

Extending down through the opening 68 in the horizontal face 70 of the bracket 58, we provide the carrying member 72 on which the floor relay armature 74 is mounted. Riveted to the armature 74, we provide the insulated switch member 76 through the opening 78 of which the movable contact elements 82 and 84 extend. The members 82 and 84 are connected in parallel by the lead 85 and are secured to one side of the line L1 by the lead 87.

When the circuit through the relay coil 60 is closed by a call or car button for a particular floor, as an example say the top or sixth floor as will hereafter be explained, the armature 74 of the unit corresponding thereto, say 36, is attracted against the tension of the spring 86 (one end of which is secured to the lug 88 on the face 70 and the other end of which is secured to the armature carrying member 72) to bring the terminal 88 on the element 82 into engagement with the terminal 91 on the member 92 and to

bring the terminal 90 on the element 84 into engagement with the terminal 94 on the member 96 to close the respective switches which they comprise.

5 When the armature 74 is released, it is returned to normal position by the spring 86 on the pivot formed by the face 70 on which the armature carrying member 72 is mounted to thereby disengage the contact 88 from the contact 94 and 10 the contact 88 from the contact 91 and thus open the respective switches formed by these contacts.

Referring now to Fig. 1, in this position, the traveler 18 and follower 38 have been moved to 15 the lowermost position whereat the elevator car has been stopped at the basement floor so that all of the cams 20 for each selector unit above the basement floor have been rotated into the 20 positions illustrated, pointing to the traveler, whereat the down direction switches have been opened and all the up direction switches closed. We shall now describe how this is accomplished by the selector unit embodying the present invention.

25 Referring to Fig. 10, each cam 20 on one face 96 thereof is provided with a nose 98 which is engaged by the cam follower 100 riveted to the resilient arm 102. The cam follower 100 comprises a roller 104 which rides on the face of the 30 cam nose 98 against which it is held by the resilient arm 102 (see Fig. 3 and Fig. 5). In Fig. 3 one of the arms of the starting and stopping control switches in rear of the directional switches now being described is broken away for clarity in 35 depicting the structure, as is done in Fig. 6.

Intermediate the resilient arm 102, we provide on each face thereof a contact 106 and a contact 108 and on the somewhat resilient arms 110 and 112 the contacts 114 and 116. The contacts 106 40 and 114 constitute an up-direction switch and the contacts 108 and 116 a down-direction switch. When the cam 20 is oscillated so that the cam follower is positioned at the lowest part 118 of the cam nose 98, the tension of the arm 102 forces 45 the cam follower thereagainst to bring the terminal 106 against the terminal 114 and thus close the up direction switch (see Figs. 10 and 19).

This is shown in the position of the cams as 50 illustrated in Fig. 1 and will occur when the cams are rotated in a clockwise direction as viewed in Fig. 1 corresponding to the down travel of the elevator car. Thus when the car is traveling down the cams of all selector units corresponding to floors above the car will have been rotated 55 into the position illustrated in Fig. 1 since the traveler 18 has moved past the unit corresponding thereto.

However when the cams are rotated in a counter-clockwise direction corresponding to the 60 up travel of the elevator car the cams 20 will be rotated in the opposite direction, to assume the position illustrated in Fig. 2. As the cam moves into this position, the high point 119 of the cam nose 98 will be brought against the follower 100 65 to thereby move the arm 102 toward the arm 112 to bring the terminal 108 into engagement with the terminal 116 and the terminal 106 away from the terminal 114 to close the down directional switch and open the up directional switch.

70 When, however, the car reaches a particular floor, the follower 38 is positioned between the arms 40 and 42, which are then in an upright position with the traveler therebetween of the floor corresponding to that unit. At this time the follower 100 is at an intermediate position

[2] of dwell on the nose 98 whereat contact 106 is disengaged from contact 114 and contact 108 is disengaged from contact 116. Thus in this neutral position, when the car is at a floor corresponding to that selector unit, both up and down directional switches are opened so that if a call is registered for that floor no circuit will be made through either the up or down directional switch for that floor but for calls registered above or below the car, proper circuits will be made through the up or down directional switches of the corresponding floor selector unit.

That is, if the car has been moved below a floor the up directional switch corresponding to that floor will have been closed so that a call will be registered for that floor by closing the circuit through the up directional switch corresponding to the floor but if the car is above the floor at which the call is registered the circuit will be made through the down directional switch corresponding to the floor.

When the car is positioned at the floor, the hall or car button of which is operated, the car will not be moved in either direction since neither the up coil or down coil may be energized because the contacts 106 and 108 are positioned out of contact with the corresponding contacts 114 and 116, the follower 100 being positioned at the intermediate or neutral point of dwell 121. It will of course be understood that impressing the hall or car button effects the opening of the car doors by conventional means and electrical circuits which are not shown since they form no part of the present invention and are well known.

The bases of the members or reeds 84, 96, 102, 110 and 112 are insulated from each other, as by the fiber insulation 113 and are mounted on the member 16 as by the elongated screw 115 extending through the member and the end plate 117. The member or reed 102 has the lead 118 secured thereto, the member or reed 110 having the lead 120 secured thereto and the member or reed 112 having the lead 122 secured thereto (Fig. 13). The lead 118 is connected to the member or reed 84 and the member 96 is connected to the lead 97 (Fig. 6).

The two members or reeds 92 and 96 are connected in parallel by means of the jump wire 85. Since the floor units are separate individual structures, the other ends of the leads 120 and 122 are free so that they may be connected to the respective up and down coil terminals.

In order to understand the operation of the floor unit with respect to starting and stopping of the car in response to a call registered by the hall or car buttons, reference will now be made more particularly to Figs. 11 to 16 in conjunction with the schematic wiring diagram illustrated in Fig. 20 with respect to the schematic wiring diagram, attention is called to the fact that only two circuit lines L1 and L2 are shown and only such elements of a conventional elevator system as are necessary for an understanding of our invention; switch contacts being shown in the open or closed position assumed by them when the car is at rest at a floor. The wiring diagram for the elements corresponding to but a single floor are shown in Fig. 15 since it is merely illustrative of the operation of a selector mechanism supplied with a floor unit according to our invention.

Upon closing either the hall button 129 or the car button 130 for any floor to which the car is to respond, a circuit is made through the floor

relay 60 corresponding to that floor through the ordinarily closed terminals mounted on the floor unit (which shall be described) on which the relay coil for that floor is also mounted.

In order to in sequence open and close these terminals as the car is moved in the shaftway, we arrange on each cam 20 of a floor unit 10, the nose 132 on the other side of the face 96 of the cam 20 and the operation of which we shall now describe.

In the position illustrated in Fig. 1, referring in the description which follows specifically however to Figs. 10 to 16 and 18, the follower 140, which also preferably has the roller 142, for all cams except on the unit for the lowermost or basement floor, is positioned at the lowest point 144 of the cam nose 132 on one side thereof (the down side). The follower 140 is mounted on the resilient member or reed 146 so that the roller 142 is always held against the face 96 of the cam 20 and in this position pushes the terminal 148 into contact with the terminal 150 on the member 152. On the other side of the member 152 is mounted another terminal 154 which is pushed into contact with the terminal 156 on the member 158. The resiliency of the member 146 brings the terminal 160 on the other face thereof out of engagement with the terminal 162 on the member or reed 164. Thus in the positions assumed by the cams for the units above the lowermost floor the switches formed by the contacts 148 and 150 and the contacts 154 and 156 are closed but the switch formed by the contacts 162 and 164 is open. It should at this point also be recognized, that the follower 100 is at the lowest point 118 on the cam nose 98 to concurrently close the switch (114 and 106) to the up coil and open the switch (108 and 116) to the down coil, all of which occurs in those floor units of the floors above which the car is positioned.

Thus a circuit will be made from L1 through a hall button 129 or car button 130, the lead 155 (one end of which is connected to the member 158 and the other end of which is free for connection in the elevator system) the switches formed by the contacts 156 and 154, terminals 150 and 148, the floor relay 60 to the line L2 (Fig. 20). The floor relay is thus energized to close the floor relay contacts 88 and 91 and 90 and 94.

It will be understood that Fig. 11 illustrates the position of the cam 20 assumed by it for all floor units above the car, in the illustration Fig. 1 for all units above unit 34; Fig. 12 illustrates the position of the cam assumed by it for the floor unit corresponding to the floor at which the cam is positioned, in the illustration Fig. 1 the unit 34; and Fig. 14 illustrates the position assumed by the cam for all floor units below the car, in the illustration Fig. 2, the units below the unit 36.

The members or reeds 146, 152, 158 and 164 are mounted on the element 16 between it and the plate 169 by means of the set screw 171 and are separated from each other by any suitable insulating means 173.

The member or reed 146 is connected to the member or reed 82 (and so the terminal 91) by means of the lead 161 and the member or reed 164 by means of the lead 163, which is free at its other end so that it may be connected in the elevator system and thus connect the stopping coil 170 into the circuit, as will be further described.

It is understood that circuits and the means for starting the elevator car in the proper direction, upon registering a call through the hall or car buttons, need not be shown as my floor selector unit may be used with any kind of elevator system, such as conventional automatic push-button types.

Upon registering a call with a hall or car button at a particular floor, as stated the floor relay coil will become energized to attract the armature 74 and close the switches formed by the contacts 88 and 91 and 90 and 94. This is accomplished since the movement of the car to the basement floor (in the illustration) has rotated the cam 20 of every floor unit above the basement floor in a clockwise direction by engagement of each arm 40 by the follower 38 as the traveler 18 is moved from left to right in Fig. 1 to close the switches connecting the hall or car buttons to the floor relay coil for the corresponding floor.

This forms a holding circuit from L1 through lead 97, jumper wire 85, terminals 88 and 91, lead 170 terminals 148 and 160, through the floor relay coil 60 to L2. Concurrently a circuit is made from L1 through lead 97, terminals 90 and 94, lead 118, terminals 106 and 114, lead 120, through the up coil 172 to the other side of the line L2, thus closing the up direction circuit for any floor above the car position, in the illustration given (Fig. 1) above the basement floor.

Since there are no floors below the basement floor, the floor unit 34 for that floor, need not be provided with the contacts 108 and 116, although we prefer to make all units standard and thus do not distinguish between them.

The cam 20 in the next position of movement as illustrated in Figs. 12 and 13 (when the car is at a floor), as it is rotated by movement of the follower 38, pushes the member or reed 148 away from the member 152, which latter in turn leaves the member 158 to bring the terminal 154 out of engagement with the terminal 156. Thus the circuit from the hall or car buttons is first broken so that the floor relay coil 60 as the car reaches the floor corresponding to that unit 10 will not continue to be energized except through its holding circuit formed by the terminals 148 and 150, as heretofore described.

Further rotation of the cam 20 by the follower 38 as the elevator moves in the up direction, further pushes the follower 140 to move the member or reed 146 away from the member or reed 152 to open the switch formed by the terminals 150 and 148 and close the switch formed by the terminals 160 and 162 leading to the stopping coil 178.

The switches formed by the terminals 162 and 160 and the terminals 148 and 150 are of the conventional make before break type. That is, the circuit is made through the stopping coil before the circuit is broken through the floor relay coil as otherwise the stopping coil could not become energized.

The circuit through the floor relay coil is broken and the circuit through the stopping coil is made when the high point 174 of the nose 132 is reached. This occurs when the follower 38 is positioned between the arms 40 and 42, as illustrated by the unit 34 in Fig. 1 and the unit 36 in Fig. 2, which happens when the car is at the floor corresponding to the particular unit.

Should the floor relay coil of a unit 10 be energized by the registration of a call thereat, as previously described, as the car reaches the corresponding floor, a circuit will be made through

the stopping coil from L1, terminals 160 and 162 (which are alive since the floor relay circuit is not yet broken), the lead 168 and the coil to L2 to close the stopping coil contacts 174. This forms a holding circuit for the stopping coil from L1, through contacts 174, the timer coil contacts 176 through the stopping coil 170 to L2. Thus, if the floor relay of a unit is energized, when the car reaches the floor corresponding thereto, it will be stopped by the operation of my unit and the circuit elements which it controls through the stopping coil.

A parallel circuit is made from L1, the contacts 174, through a conventional timer coil 178 to L2. Therefore, after the lapse of a selected time, the timer coil contacts 176 are opened to break the circuit through the stopping coil 170 and place the system in condition for its further operation by de-energizing the stopping coil 170.

If a call is not registered at a particular floor, the car will continue to move therewith since the stopping coil will not be energized, bringing the follower 38 into engagement with the arm 42 to rotate the cam 20 into the position illustrated in Fig. 2 by all the units, except that 36 for the top floor. This is shown in Figs. 14 and 15.

In this position the follower 142 is moved beyond the high point 174 of the cam to the low point 180 thereof (Fig. 18), whereat the member or reed 146 moves away from the member or reed 164, to open the stopping coil circuit for that floor, and toward the member and reed 152 to push it toward the member or reed 158 and thus close the circuit from the hall or car button through the floor relay coil for that unit that has been passed and thus place the unit in condition to have the coil 64 therefor energized for registration of a call.

Concurrently the follower 190 reaches the high point 119 of the cam nose 98 (Fig. 19) to open the coil 172 and close the down coil 182. Thus when the car passes a floor unit going in the up direction, it will again spontaneously close the switch formed by the contacts 108 and 116 to the down coil and simultaneously open the circuit to the up coil and concurrently place the unit in condition to have a call registered at that floor by placing the floor relay coil therefor in condition to be energized.

It should be noted that, if the hall or car button is held "in," even after the car starts to move other calls, may nevertheless be registered since the circuit is first broken through the hall or car buttons immediately after the car reaches the floor when terminal 154 is moved away from terminal 156.

In operation, should the car be at the basement floor as illustrated in Fig. 1 and a call be registered at the top floor, movement up of the car is initiated by conventional means but in the up direction since the contacts 114 and 106 in the up coil 172 circuit for the unit corresponding to the top floor have been closed by our novel unit construction, the floor relay coil of the unit 36 corresponding to the top floor is energized and the car stopped when the follower 38 is positioned as illustrated in Fig. 2. Should the floor relay coil of any floor unit below it be energized, the car will stop at that floor first, since the member or reed 146 for that floor unit is moved toward the member or reed 164 to close the circuit through the stopping coil therefor.

As each cam 20 is rotated into the position illustrated in Fig. 2 (car moving up) the circuit to the up coil is opened and the circuit to the down

coil closed. Thus if the car is above a floor it must move downward to a floor below and if the car is below a floor it must move upward to a floor above the car since the directional circuits are spontaneously placed in operative condition by the car movement in either direction.

It should be noted here that, if desired, since there will be no calls registered for floors above the top floor, the switch comprised by the terminals 166 and 114 leading to the up coil, for the top floor unit may be dispensed with, although for reasons of convenience in standardizing the units, as stated with reference to the bottom floor unit, we preferably do not distinguish between it and any other floor unit.

Should the car, for example, be at the top floor, as illustrated in Fig. 2 and a call registered at a floor below, for example at the lowermost floor, each cam will be moved in a clockwise direction by engagement first of the arm 42 and then the arm 40. This causes the follower 140 to be moved from the low point 180 of the nose 132 (on the up side) through the high point 174 neutral or intermediate, the car at the floor, to the low point 144 (on the down side) and the follower 100 to be moved from the high point 119 of the nose 93 (on the up side) through the intermediate or neutral point 121, the car at the floor, to the low point 118 (on the down side). It should be noted again, that when the car moves from a lower floor to a higher floor, the cam 20 is rotated in a counter-clockwise direction to reverse the movement of the followers 140 and 100.

Through unforeseen circumstances the car may be stopped above or below a floor because the arms 40 or 42 may have changed their position relative to the position of the car relative to the floor landing. A fraction of an inch displacement of an arm may mean that the car will be stopped inches above or below the corresponding floor landing. In order to provide means for easily adjusting the position of the arms 42 and 40 with respect to the follower 38, I preferably provide the construction illustrated in Fig. 17.

The arms 40 and 42 are made from an integral member 184 formed from flat plate spring steel, which is folded over upon itself about the periphery of the cam 20 to straddle it. The member 184 intermediate its free ends, which form the arms 40 and 42, is secured to the cam 20 by means of the set screw 186.

Extending through the upper end of the cam 20 and each arm 40 and 42, we provide the threaded element 188 on one end of which is threadedly mounted the knurled set screw 190, the arm 40 being positioned between it and the cam 20, and on the other end of which the knurled set screw 192 is threadedly mounted, the arm 42 being positioned between it and the cam 20.

Each arm is tensioned against its corresponding adjusting set screw so that movement of the set screw will selectively force the corresponding arm toward the cam 20 or permit it to move away therefrom against the set screw, as illustrated by the broken lines of Fig. 17. Thus the arm 40 or 42 may be easily adjusted in position to cause the elevator to stop at the desired point in the hatchway without the necessity of taking the floor selector unit apart or electrically disconnecting it from the system.

It will now be apparent that we have provided a floor selector unit in which the switches required to determine the direction of car movement, initiating starting and stopping of the car, registration of a call for a floor and the floor relay

coil are grouped for a given floor in a single unitary structure that will be standard for all buildings.

We have only shown such details of a conventional automatic elevator system as are required for an understanding of our invention since they can be supplied by those skilled in the art to whom this description is directed. It will of course be understood that our invention may be applied to either alternating or direct current installations and to installation of more than one speed.

While we have shown in some detail a specific embodiment of our invention, we do not intend to be limited thereto, but desire to claim our invention as broadly as the appended claims and the prior art will permit.

We claim:

1. A floor unit for a selector mechanism comprising a supporting structure, a relay mounted on said structure having an armature movable toward and away from the coil thereof, a pair of normally open switches connected in parallel and closed by the armature upon energizing the coil, 25 a cam mounted for movement on the structure, an up direction and a down direction switch controlled by the cam to open the down direction switch and concurrently close the up direction switch at one position of the cam movement and to open the up direction switch and concurrently close the down direction switch at another position of the cam movement, said cam concurrently opening both up and down direction switches in an intermediate position of the cam movement, 35 said up and down direction switches connected in parallel to one of said pair of normally open switches, a second pair of normally closed switches connected to the coil and to the other of said normally open switches and a last mentioned normally open switch for connection to a stopping coil, said first mentioned normally open switches closed upon energizing said coil, said normally closed switches opened by said cam and the last mentioned normally open switch closed by said cam at said intermediate position of the cam movement.

2. In a floor unit for a selector mechanism, a supporting structure, a coil mounted on said structure, an armature normally resiliently held away from said coil, a pair of switches controlled by said armature to be closed thereby upon energizing the coil, a cam movable from a first position to a second position and back to the first position, an up direction and a down direction switch, a nose on the cam for operating the up and down direction switches and having a low point at one of said positions, a neutral point intermediate said positions and a high point at the other of said positions said nose at the low point opening one of said up and down direction switches and concurrently closing the other of said up and down switches and at the high point closing the first mentioned of said up and down direction switches and concurrently opening the second mentioned of said up and down switches, said up and down switches connected in parallel to one of the pair of switches controlled by said armature, a group of switches comprising a pair of normally closed switches and a normally open switch, a second nose on said cam for controlling said group of switches, said second nose having a low point at one of said cam positions whereat the closed switches and the open switch of said group are in normal position, a high point at said intermediate position whereat the normally closed

switches of the groups are open and the open switch of the group is closed and a second low point at the other of said cam positions whereat the closed switches and the open switch of said group are in normal position.

3. The floor unit of claim 2, said first normally closed switch of said group being opened by the cam before the second normally closed switch of said group is opened.

4. The floor unit of claim 2, said group of switches being of the make before break type.

5. In a floor unit for a selector mechanism, an up direction and a down direction switch, a group of switches comprising a normally closed switch and a normally open switch and a cam movable between two positions for concurrently operating the switches, the up direction switch being open and the down direction switch being closed at one position of the cam movement and the up direction switch being closed and the down direction switch being open at the other position of the cam movement, said group of switches being in normal condition at both positions of cam movement and said up and down direction switches being open at an intermediate position of cam movement, the said normally closed switch of said group being open and the normally open switch of said group being closed at said intermediate position of cam movement.

6. In a floor unit for a selector mechanism, a supporting structure, a cam, a shaft on the structure and carrying the cam, cam noses on one face of the cam and separated by the shaft, the profile of one cam nose having a low point, a high point and a neutral point intermediate the low and high point, the profile of the other cam nose having a high point intermediate two low points, said neutral point on the first cam nose and said high point on the second cam nose being radially opposite each other and said high point on said first cam nose being radially opposite a low point on said second nose and said low point on said first nose being radially opposite the other low point on said second cam nose, an up and a down direction switch having a common member, said common member engaged by the first nose to open and close the up and down switches upon movement of the cam on the shaft, and a pair of switches having a second common member, said second common member engaging said second nose to open and close each one of said pair of switches.

7. In a floor unit, a supporting structure, a coil, an armature mounted in the structure for attraction of the armature upon energizing the coil, a pair of normally opened switches controlled by the armature and closed upon energizing the coil, one side of said switch for connection to one side of a circuit, a second pair of switches, one of said switches being normally opened and the other of said switches being normally closed, said switches having a common member, one side of said switches connected to the coil and the other side of said switches for connection in the system, the common member being connected to one of the switches controlled by the armature, an up and down switch having a common member, said common member of the up and down switch being connected to the other side of said other switch controlled by the armature and a cam rotatably mounted on the structure for opening and closing each of the said first pair of switches upon movement of the common member therefor and concurrently in selective sequence opening and clos-

ing the up and down switch upon movement of the common member therefore.

8. In a floor unit, a cam, a group of three switches connected in series, the first pair of switches of said group having a common movable member, the following pair of switches of said group having a second movable common member, and a group of two switches having a movable common member, the first two switches of said group of three switches being normally closed and the third switch of said group of three switches being normally open, said cam moving the movable common members of said group of three switches to in sequence open the first two switches and close the third switch, said third switch being closed before said second switch is open and said cam opening both switches of said group of two switches upon closing the third switch of said group of three switches and one switch of said group of two switches being opened and the other of said group of two switches being closed upon opening the third switch of said group of three switches.

9. In a floor unit, a cam movable between two positions, a group of switches connected in series and having a common movable member, said cam, upon movement in one direction to an intermediate position, moving the common member to open one switch of said group and close another switch of said group, said cam at both positions moving the common member to close the first switch of said group and open the second switch of said group and a second group of switches having a second common movable member, movement of the second common member by the cam at one position closing one of said second group of switches and concurrently opening the second of said group of switches and at the other position opening the first switch of said second group of switches and concurrently closing the second of said second group of switches, both of said switches of said second group of switches being opened at the intermediate position of the cam by movement of the said second common member.

10. In a floor unit for a selector mechanism having a relay mounted thereon, a pair of switches for energizing the relay to register a call at the floor unit and for energizing a coil to initiate stopping of an elevator car, said switches having yieldable arms, one arm being common to both switches and a cam mounted for oscillation between two positions and engaging the common arm to in sequence open and close said switches, said first mentioned switch being closed and said second mentioned switch being opened at both positions by movement of the common arm by the cam and said second mentioned switch being closed and the first mentioned switch being opened at an intermediate position by movement of the common arm by the cam.

11. In a floor selector unit for a selector mechanism having a relay mounted thereon, an up direction and a down direction switch, said switches having yieldable arms, one arm being common to both switches, said common arm being connected in a circuit including said relay and a cam mounted for oscillation between two positions and engaging the common arm, one of said up and down switches being closed and the other of said up and down switches being opened at one position by movement of the common arm by the cam and the first of said up and down switches being opened and the second of said up and down switches being closed at the other of said positions by movement of the common arm by the

cam, both of said up and down switches being opened at an intermediate position by movement of the common arm by the cam.

12. In a floor selector unit for a selector mechanism having a relay mounted thereon, a call registering switch, a switch for initiating the stopping of a car, an up direction switch, a down direction switch and means, movable between two positions, for opening and closing said switches, said registering switch being closed at both positions and opened at an intermediate position by said means, said initiating switch being opened at both positions and closed at the intermediate position by said means, and one of said direction switches being closed and the other direction switch being opened by the means at one position, the other direction switch being closed and the first direction switch being opened by the means at the other position, both direction switches being opened by the means at the intermediate position.

13. In a floor unit for a selector mechanism; a floor relay coil; a stopping coil; a plurality of electrodes forming a group of switches having a common member, the common member movable between a first and second electrode of said electrodes and being connected to the floor relay coil, said first electrode, common member and relay coil in a first circuit and said second electrode, common member and floor relay coil in a second circuit, a third electrode of said electrodes against the second electrode, a fourth electrode of said electrodes coupled to said stopping coil; said stopping coil arranged in a third circuit having contacts therein controlled by the stopping coil; said third electrode, fourth electrode and said stopping coil in a fourth circuit; a timer coil connected in said third circuit in parallel with the stopping coil; and contacts controlled by the timer coil in the parallel branch of said third circuit in which the stopping coil is arranged.

14. In a selector mechanism for an elevator system having an elevator car movable in an up direction and in a down direction for serving a plurality of floors, said elevator system having coils for causing movement of the car in the up and the down direction a plurality of floor units, each one of said floor units corresponding to a floor, a plurality of said floor units, each unit removably mounted in the selector mechanism to form a side by side group thereof, a traveler reciprocably movable from and between each end of the group of units, a cam rotatably mounted in each unit, an arm extending up from each side of the cam in a unit in the path of movement of the traveler across the selector mechanism in position to be engaged by the traveler upon movement thereof across the selector mechanism to thereby rotate the cam, each unit having a down direction switch for connection to a coil for causing movement of an elevator car in the down direction and an up direction switch for connection to a car for causing movement of the elevator car in the up direction, each down direction switch of each floor unit being open when the up direction switch of that unit is closed and each up direction switch of each unit being open when the down direction unit of that switch is closed, a floor relay coil for initiating move-

ment of the elevator car, each unit having a switch connected to the floor relay coil, said switch connected to the floor relay being closed upon oscillation of the cam by engagement of the arm by the traveler.

15. The selector mechanism of claim 14, said arms being resilient to permit movement thereof past of the traveler.

16. The selector mechanism of claim 14 and including a member extending through the arms on each side of a cam on a unit and a means on the member in engagement with each cam for selectively adjusting the position of each arm with respect to the cam to thereby select the position whereat the arm is engaged by the traveler.

17. A floor selector for an automatic elevator system serving a building having a plurality of floors and said system having a car reciprocable between a first terminal floor and a second terminal floor and comprising a housing, a traveler mounted in the housing for reciprocation thereacross corresponding to movement of the car between the first terminal floor and the second terminal floor, a plurality of cams spaced in a line of cams in the housing in the path of reciprocation of the traveler, each cam corresponding to a floor of the building, a first of said plurality of cams at a first end of said line of cams corresponding to the first terminal floor and a second of said plurality of cams at a second end of said line of cams corresponding to the second terminal floor, a pivot securing each cam in the housing, an arm secured on each side of each cam and in the path of reciprocation of the traveler whereby the cam is moved counterclockwise on the pivot upon engagement of an arm and movement of the traveler from the first end toward the second end of the line of cams and in clockwise direction on the pivot upon engagement of the other arm and movement of the traveler from the second end toward the first end of the line of cams, a group of switches to be selectively and sequentially opened and closed upon movement of the cam by the traveler, a pair of switches to be selectively opened and closed by movement of said cam in sequence with the opening and closing of said group of switches, and including a member extending between and through the arms on each cam and an adjusting means for selectively positioning each arm on a cam relatively to the said cam.
